RELAY SYSTEM

Anthony H. Lamb, Elizabeth, N. J., assignor to
 Weston Electrical Instrument Corporation,
 Newark, N. J., a corporation of New Jersey

Application November 23, 1936, Serial No. 112,423

11 Claims. (Cl. 172—239)

This invention relates to relay systems and particularly to relay systems of the type which includes an instrument type relay controlling the operation of a reversible motor or equivalent devices for effecting changes in a positive or negative sense.

An object of the invention is to provide a relay system including a reversible control element and a sensitive relay for actuating the control element, these devices being operatively connected through a circuit that includes mechanism for limiting each control operation to not more than a limited period or "control pulse". An object is to provide a relay system including a sensitive relay for closing alternate circuits which each include an auxiliary relay for closing a holding circuit and one energizing circuit of a reversible motor, and a pulsing device for limiting the operation of the reversible motor to a comparatively short period or pulse. An object of the invention is to provide relay systems of the type stated in which the pulsing device opens a switch in the circuit of the auxiliary relays, thereby de-energizing the same to stop the motor, and then closes the switch to permit a subsequent energization of the auxiliary relays by the sensitive relay. More specifically, objects are to provide relay systems of the type stated in which the pulsing device is actuated by the reversible motor or by an independent motor that is energized by the sensitive relay.

These and other objects and advantages of the invention will be apparent from the following specification when taken with the accompanying drawing in which:

Fig. 1 is a circuit diagram of a relay system embodying the invention;

Fig. 2 is a fragmentary circuit diagram of a modified arrangement of the portion of the Fig. 1 system at the right of line A—A, Fig. 1;

Fig. 3 is a vertical section through the double pulsing device shown in Fig. 2; and

Fig. 4 is a fragmentary circuit diagram illustrating a thermal type of pulsing device.

In the Fig. 1 diagram, the essential circuits for the flow of current to the reversible control device are shown in heavy line, and other circuits are shown in light line.

The primary or instrument relay is indicated diagrammatically by the moving coil 1 of an electrical measuring instrument, the coil carrying a pointer 2 that has a rider 3 of magnetic material for cooperation with a pair of stationary contacts 4, 4' in the form of small permanent magnets. A "pusher" system for separating the

magnetic rider from the magnet contacts is shown as a pair of pivoted arms 5, 5' that are moved towards each other by the solenoid 6. Sensitive instrument relays of this type are described in detail and claimed in my copending application Ser. No. 6,891, filed Feb. 16, 1935, now Patent No. 2,062,915, granted Dec. 1, 1936.

The control device 7 to which the moving coil is connected will depend upon the particular quantity or factor that is to be maintained at some desired value by the relay system. The device 7 may be a thermocouple in the case of temperature control, the line or a resistor in the line in the case of the control of voltage to a load circuit, a photocell in the case of illumination or smoke control, or the device 7 may be one of these or other variation producing devices in other types of control, recording and/or alarm systems.

A source of current is connected between a pair of terminals 8, and one terminal is connected to the pointer 2 of the instrument relay by a lead 9. The relay contacts 4, 4' are connected to the solenoids 10, 10' of auxiliary relays by leads 11, 11', respectively, and a common lead 12 extends from the solenoids to a contact 13 of a pulse controller or pulsing device. The pulsing device is shown as a multi-lobed cam wheel 14 having undercut teeth which permit the contact to lose contact with the wheel momentarily as the wheel is given a step-by-step rotation in counter-clockwise direction by the pawl 15 carried by armature 16 of the solenoid 17. A contact 18 which bears continuously on the toothed contact wheel 14 is connected to the other terminal 8 by a lead 19. A spring 20 draws the contact 13 towards the wheel 14 and one of the described circuits (either through solenoid 10 or solenoid 10') is therefore completed between the terminals 8 when the pointer engages one of the relay contacts.

Each auxiliary relay controls two normally open switches 21, 22 and 21', 22', respectively, that have contact arms connected to one terminal 8 of the power source by a lead 8'. The switches 21, 21' are holding switches for the solenoids 10 and 10', and their contact points are connected to leads 11, 11', respectively. The contact points of switches 22, 22' are connected to circuit elements 23, 23', respectively, of a reversible control device 24. The common return 25 for the alternatively energized circuit elements 23, 23' may be connected either to the contact arm 18 of the pulsing device or directly to the lead 19 from the second terminal 8 of

- the power source. As shown in Fig. 1, the lead 25 extends to a switch arm 26 that may be engaged with a contact of the lead 27 to the contact strip 13 or a jumper 28 to the lead 19.
- 5 The circuit elements 23, 23' may be the "direct" and "reverse" field windings when the control device 24 is a motor for adjusting a tap along a resistance, for actuating valves or for driving other forms of regulating apparatus in 10 opposite directions. The circuit elements 23, 23' may be electromagnets for shifting a regulating element between alternative control positions, or the circuit elements may be visual or audible signal devices in the case of an alarm circuit.
- 15 The exact design and the operating characteristics of the alternative or reversible control device 24 may be varied at will in accordance with particular type of automatic regulator or alarm that is desired.
- 20 A divided resistor 29 is shunted across the circuit elements 23, 23' of the control device 24, and leads 30, 31 extend from the midpoint of the resistor to the solenoid 6 of the pusher arm system and to the solenoid 17 of the pulsing device. The circuits for these solenoids are completed to the switch arm 26 by leads 32, 33, respectively, and a common lead 34.
- 25 The relay system operates in the following manner when, as illustrated, the switch arm 26 is closed on the jumper 28. The pointer 2 of the instrument relay is displaced in accordance with variations in the output of the unit 1 which, for convenience of description, will be assumed to be a thermocouple in a space that is to be maintained at some predetermined temperature.
- 30 A drop in temperature will carry the pointer 2 adjacent a magnet contact, said contact 4, and magnetic attraction draws the rider 3 firmly against contact 4. This completes a circuit through the solenoid 10 as follows: from upper terminal 8, lead 9, pointer 2 and contact 4, lead 11, the solenoid 10, lead 12, contact arm 13, cam wheel 14, contact arm 18, and lead 19 to the other terminal 8. Auxiliary relay switches 21, 22 are thereby closed; the switch 21 completing a holding circuit for solenoid 10, and the switch 22 connecting lead 9 to the coil or element 23 of the reversible device 24. Current flow is thereby established through coil 23 since the lead 25, switch 26, jumper 28 and lead 19 complete the circuit back to the terminal 8. Current flow is also established through the upper section of resistor 29 to the resetting solenoid 6 and to the pulsing solenoid 17, through leads 30-34, inclusive.
- 35 Energization of solenoid 6 causes pusher arm 5 to separate the pointer 2 from magnet contact 4, but the auxiliary relay is still energized through the holding switch 21. Energization of solenoid 17 results in a turning of the cam wheel 14 counter-clockwise and the auxiliary relay circuit is momentarily broken as the contact arm 13 of the pulsing device drops from one tooth to the next. Switches 21 and 22 drop open at 40 the momentary interruption of this circuit, thus opening the holding circuit of solenoid 10 and the circuit to coil 23 of the reversible device 24. The entire system is thus reset for another cycle of operations.
- 45 In the assumed case of a temperature control, the reversible control device 24 will actuate a variable resistance or a valve to increase the heating effect when the coil 23 is energized. If the temperature is still too low when the pusher arm 5 returns to normal position upon the open-

ing of the circuit through relay switch 22, the primary relay contacts 3, 4 close again, and the described operations are repeated. A rise in temperature results in an engagement of contacts 3, 4 of primary relay, thus energizing solenoid 10' to close switch 22' of the coil 23' of the reversible device 24. This results in an adjustment of the heat control element (resistance or valve) in the reverse sense to decrease the heat supply.

10 When the switch arm 26 is closed on lead 27, the opening of the main circuit at the pulsing device interrupts the current supply to the auxiliary relays, the reversing device 24 and the solenoids of the pulsing and pusher device. This direct opening of the circuit of the reversible device 24 by the pulsing device provides a substantially shorter control cycle than is obtained in the other position of switch arm 26, particularly when the auxiliary relays 10, 10' are designed for slow opening.

15 The above description refers to control operations but it will be apparent that the device 24 may be merely an alarm device in which the elements or coils 23, 23' actuate distinctive signals.

20 The pulsing device may be actuated by the reversible device 24, and one construction of this type is illustrated in Figs. 2 and 3. The device 24 comprises a motor having an armature 35 30 that turns in different directions in accordance with the particular field winding 23 or 23' which is energized. The armature is connected through reduction gearing 36 to a control shaft 37 having a threaded end for displacing a control rod 38. 35 A pair of contact wheels 14a, 14b are mounted on shaft 38 that is axially aligned with and insulated from the shaft 37, the lobes of the wheels extending in opposite directions and the wheels being connected to the shaft by oppositely arranged one-way clutches 40 of known type for the counter-clockwise rotation of wheel 14a and the clockwise rotation of wheel 14b. Contact arms 13a, 13b engage the respective wheels to form a pair of switches that are in series between the lead 19 from a source terminal 8 and the junction of the motor return 25' and the auxiliary solenoids return 12'.

40 If the shafts 37, 38 rotate clockwise upon the energization of field winding 23, the wheel 14a 50 of the pulsing device remains stationary and the wheel 14b rotates with shaft 38 to open the motor and auxiliary relay circuits when contact arm 13b drops from the end of one cam lobe. The system is thus reset for the next cycle of operations. 55

45 As shown in Fig. 4, the pulsing device may be a thermal switch having a bimetallic strip 41 that is deflected from normal closed circuit position by a heating coil 42 that is in series with the switch.

50 The duration of one control cycle or pulse is preferably so related to the speed of correction that the minimum desired correction will be effected in one cycle or pulse. Over-correction or hunting will be avoided when this relation exists and, for larger corrections, a number of control actions take place in quick succession as the pulsing device restores the system to operative condition immediately after the termination of each control operation or pulse.

55 It will be apparent that the invention is not limited to the specific circuits and elements herein illustrated and described, and that various changes may be made without departing from the 78

spirit of my invention as set forth in the following claims.

I claim:

1. A relay system comprising a primary relay having magnetic contacts, an auxiliary relay in a circuit including said magnetic contacts, said auxiliary relay including a holding switch in shunt with the magnetic contacts and a load circuit switch, means energized by said load circuit switch for separating the magnetic contacts, and a pulsing device for limiting the energization of said auxiliary relay through said holding switch to not more than a predetermined interval.
2. A relay system comprising a primary relay having a contact arm movable between two fixed contacts, an auxiliary relay in circuit with each fixed contact, each auxiliary relay including a control circuit switch and a holding switch in shunt with the contact arm and the fixed contact of the associated auxiliary relay, a reversible device having the operating elements thereof included in the respective control circuits, a normally closed pulsing switch for opening the circuits of the auxiliary relays, said pulsing switch comprising two multilobed contact wheels with reversely arranged lobes and contact strips bearing upon the edges of the respective wheels, and means operable by said reversible device for actuating said pulsing switch.
3. In a relay system, the combination with a primary relay having a contact arm carrying a magnetic rider and movable between two fixed magnetized contacts, a primary circuit having parallel portions each including the contact arm and one fixed contact, an auxiliary relay in each of said parallel portions of the primary circuit, each auxiliary relay including a holding switch for that relay and a control circuit switch, a reversible device having a pair of alternatively operable elements in circuit with the respective control circuit switches, normally closed pulsing switch means in said primary circuit, means energized by the closing of said primary circuit by the primary relay for actuating the pulsing switch means to open and thereafter to closed position, and means energized by a closure of the magnetic rider upon either magnetized contact for separating the magnetic rider from the contact subsequent to the closing of the holding switch by the energized auxiliary relay.
4. In a relay system, the combination with a primary relay having a contact arm movable between two fixed contacts, a primary circuit having parallel portions each including the contact arm and one fixed contact, an auxiliary relay in each of said parallel portions of the primary circuit, each auxiliary relay including a holding switch for that relay and a control circuit switch, a reversible device having a pair of alternatively operable elements in circuit with the respective control circuit switches, normally closed pulsing switch means in said primary circuit, and means actuated by said reversing device at each operation thereof to open and thereafter to close said pulsing switch means.
5. In a relay system, the combination with a primary relay having a contact arm movable between two fixed contacts, a primary circuit having parallel portions each including the contact arm and one fixed contact, an auxiliary relay in each of said parallel portions of the primary circuit, each auxiliary relay including a holding switch for that relay and a control circuit switch, a reversible device having a pair of alternatively

operable elements in circuit with the respective control circuit switches, and normally closed pulsing switch means in said primary circuit, said pulsing switch means including a bimetallic actuating strip and a heater therefor included in said primary circuit, whereby a closure of the primary circuit by the primary relay energizes the heater to effect an opening of said pulsing switch means by the bimetallic actuating member.

6. In a relay system, the combination with a primary relay having a contact arm movable between two fixed contacts, a primary circuit having parallel portions each including the contact arm and one fixed contact, an auxiliary relay in each of said parallel portions of the primary circuit, each auxiliary relay including a holding switch for that relay and a control circuit switch, a reversible device having a pair of alternatively operable elements in circuit with the respective control circuit switches, normally closed pulsing switch means in said primary circuit, means energized by the closing of said primary circuit by the primary relay for actuating the pulsing switch means to open and thereafter to closed position, and means for adjusting the length of the operating period of said reversible device upon an energization thereof; said last means including circuit elements and a switch for completing the circuit of the device in series with or alternatively in shunt with said pulsing switch means.

7. In a relay system for operating a reversible motor in opposite directions in pulses of limited duration, the combination with a reversible motor having alternatively operable windings, and a control circuit having said windings in parallel branches thereof, a control circuit switch in each of said parallel branches and an auxiliary relay for actuating each switch, means including a primary relay for establishing current flow alternatively in circuits including the respective auxiliary relays, thereby to control current flow in said branches of the control circuit, normally closed pulsing switch means operable to interrupt current flow in a common portion of said control circuit, and means actuated by said reversible motor for opening and thereafter closing the pulsing switch.

8. In a relay system, the combination with a primary relay having a contact arm movable between a pair of fixed contacts, and a reversible device having an alternatively operable winding, of a pair of auxiliary self-holding relays in circuit with the respective fixed contacts, switches actuated by said self-holding relays for controlling current flow alternatively in circuits that include the windings of said reversible device, and pulsing means for restricting the energization of said self-holding relays to a limited period; said pulsing means comprising normally closed switch means operable by said reversible motor.

9. A relay system as claimed in claim 8, in combination with manually operable switch means for completing the circuits of said windings of the reversible device alternatively in series with or in shunt to said pulsing device.

10. A relay system as claimed in claim 8 wherein said pulsing means comprises a pair of multi-lobed contact wheels having the lobes thereof reversely arranged, means including one-way driving connections for actuating said contact wheels from said reversing device, and a contact strip bearing upon each contact wheel; said contact strips and wheels comprising serially ar-

ranged circuit elements in the primary relay circuit that includes said contact arm.

11. In a relay system, the combination with a primary relay having a contact arm movable between a pair of fixed contacts, and a reversible device having alternatively operable windings, of a pair of auxiliary self-holding relays in circuit with the respective fixed contacts for con-

trolling the energization of the windings of said reversible device, and pulsing means for restricting the energization of said self-holding relays to a limited period; said pulsing means comprising normally closed switch means and means including said reversible device for actuating the same.
